UNITED STATES PATENT OFFICE.

JOHN HOLROYD, OF WASHINGTON, DISTRICT OF COLUMBIA.

IMPROVEMENT IN PROJECTILES FOR FIRE-ARMS.

Specification forming part of Letters Patent No. 25,967, dated November 1, 1859.

To all whom it may concern:

Be it known that I, JOHN HOLROYD, of Washington city, District of Columbia, have invented a new and useful Improvement in Projectiles for Fire-Arms; and I do hereby declare that the following is a full, clear, and exact description of the same, reference being had to the annexed drawings, forming part of this specification, in the several figures of which similar characters of reference denote the same parts.

Figure 1 is a side view of my shell. Fig. 2 is a front view of the same. Fig. 3 is a rear view.

This invention has reference to an improvement in projectiles for fire-arms; and its nature consists in having an elongated conical shell with a flat base, on the rear end of which are six or more curved grooves running inward from the point *a* about one-fourth the length of the shot; also, in having reversed, curved grooves running from point *a* toward the point of the shell, and in cutting away the body of the shell toward the front grooves, so as to allow the air to act upon them.

In the drawings, *S* is the shell, having the curved grooves *A* on the rear running inward from point *a*, and the reversed-curved grooves *B* on the front of the shell, also starting from point *a*. The shell is fired in the usual manner, and by the action of the gases from the charge on the grooves *A*, a rotation is given to the shell, causing it to move forward point foremost, and be exploded by the striking of the point, any suitable device being employed for effecting the discharge, and the air acting upon the grooves *B*, on the front part of the shell, serves to steady it during its passage.

I claim—

Constructing the projectile with the reversed-curved grooves *A* and *B* on the rear and front, substantially as and for the purpose set forth.

In testimony whereof I have hereunto signed my name before two subscribing witnesses.

JOHN HOLROYD.

Witnesses:
